UNITED STATES PATENT OFFICE.

JOHN FRANCIS BOORAEM, OF GREENWICH, CONNECTICUT, ASSIGNOR TO AMERICAN ENAMELED BRICK & TILE COMPANY, OF NEW YORK, N. Y., A CORPORATION OF NEW YORK.

METHOD OF PACKING ENAMEL BRICK.

Application filed June 9, 1922. Serial No. 567,067.

To all whom it may concern:

Be it known that I, JOHN FRANCIS BOORAEM, a citizen of the United States, and a resident of Greenwich, county of 5 Fairfield, and State of Connecticut, have invented a certain new and useful Method of Packing Enamel Brick, of which the following is a specification.

This invention relates to an improved 10 method of packing enamel brick or other friable articles to protect the same against breakage during transportation.

Heretofore, in the shipment of brick two general methods of packing the same in the 15 cars have been employed. In one method of packing, the bricks are placed in individual paper jackets or wrappers, the wrapper extending over one end of the brick. These individual wrappers are relatively expensive and also, considerable time 20 is consumed in placing the bricks in such wrappers prior to packing the brick in the cars. Another method which has been used is to lay long straw between the adjacent 25 brick rows. The enameled faces of the bricks are uppermost and straw is also laid between the superposed layers of brick. Frequently, this straw is of very poor 30 quality and due to carelessness in placing the straw, considerable breakage often results from shifting movements of the brick rows caused by inertia in stopping and starting the train and non-uniform thickness of straw.

35 It is, therefore, the primary object and purpose of my present invention to provide a new method of packing enamel brick which may be easily performed with a minimum of labor as the brick are packed into 40 the cars, will afford a complete protection to the brick against breakage, and in which the packing material is comparatively inexpensive, although of uniform thickness.

With the above and other objects in view, 45 the invention consists in the improved method of packing enamel-brick, as will be hereinafter more fully described, illustrated in the accompanying drawings and subsequently incorporated in the subjoined claim.

In the drawings wherein I have disclosed several practical embodiments of the present invention and in which similar refer-

ence characters designate corresponding parts throughout the several views, 55

Figure 1 is a perspective view illustrating the first step in preparing the packing material;

Figure 2 is a perspective view showing the arrangement of the packing strips in 60 connection with the individual rows of brick extending transversely of the car;

Figure 3 is a perspective view of a slightly modified form of the packing which may be employed in which the packing is 65 in the form of a corrugated sheet substantially of the same dimensions as the interior of the car;

Figure 4 is a similar view showing the arrangement of the packing sheet in Figure 70 3 in connection with the brick rows, and

Figures 5, 6, 7 and 8 illustrate another alternative embodiment of the invention.

In carrying out my invention, in one embodiment thereof I preferably use corrugated paper as the packing material. As shown in Figure 1 of the drawings this paper may be obtained in the form of a roll 5 wound upon a suitable mandrel 6. The paper roll is supported upon one end of the 80 table 7 and as the paper is withdrawn from the roll over the surface of the table it is cut off in lengths substantially equal to the interior width of the car to be loaded. This width varies from 4' 6" to 6' 6". The table 85 7 may be provided with a suitable adjustable gauge as will be obvious, so as to properly position the end of the paper sheet with relation to the point at which the cutting knife 90 is located, in accordance with the predetermined width of the car. The corrugated paper sheet either as it is withdrawn from the roll or subsequently, is scored on a line in spaced relation to one edge thereof, as indicated at 8. The distance between the score line and the longitudinal edge of the sheet is equal to or greater than the width of the brick, approximately 4", for bricks of the standard size which are 8" long, 2½" thick and 3¾" in width.

In packing the bricks in the cars the strips of corrugated paper are laid transversely of the car floor as each transverse row of bricks is packed in the car. The bricks are positioned on edge with their longer dimensions 105 extending longitudinally of the car and the

enameled surfaces of the bricks at the top. One end of the transverse row of bricks is disposed substantially at the score line 8 while the other ends of the bricks are in line with the remote longitudinal edge of the packing strip. Thus it will be understood that the wider portion 9 of the corrugated paper strip is interposed between the lower edge faces of bricks and the car floor. 5 The longitudinal edge portion of the packing strip is then bent upwardly along the score line 8 to provide an upstanding cushioning web 10 over the ends of the bricks. The next transverse row of bricks 10 is laid upon a second packing strip in a similar manner with said bricks engaged at one of their ends against the outer side of the upstanding web portion 10 of the packing strip which was transversely laid. In 15 this way the packing of the bricks in transverse rows continues for the full length of the car. Before packing the next superposed transverse rows of bricks upon those previously laid, the packing strips of corrugated paper are first positioned with their wider portions 9 upon the enameled surfaces of the brick rows previously laid so that when the bricks are arranged upon said packing strips, the enameled faces of the 20 lower row of bricks will be protected against injurious abrasive action or chipping. In this manner the packing of the bricks continues until the car is entirely filled. It will be seen that the corrugated packing 25 paper is interposed between the opposed faces of the adjacent brick rows both longitudinally and vertically of the car. Thus if any shifting of the bricks should occur through inertia in stopping or starting the 30 train, the corrugated packing strips acting as a cushioning medium will prevent chipping or breakage of the brick ends or injury to the enameled faces of the brick. The corrugated packing paper in strip form is 35 easily handled and may be very quickly arranged in proper position as the brick are packed into the car, thus greatly expediting the packing of the car over the time consumed in the use of methods heretofore in 40 vogue.

In Figs. 3 and 4 of the drawings I have illustrated a slightly different form of the packing material which may be used in carrying out the present method. In this 45 case, corrugated paper sheets 11 of car width and of predetermined length are formed with transversely extending rectangular channels 12 alternately opening upon opposite sides of the sheet. These sections are of such length that they can be 50 easily handled and a predetermined number of such sections successively laid end to end as the transverse rows of bricks are packed in the car substantially provide a continuous 55 packing sheet extending the entire length

of the car. In this case the sections of packing may be most readily placed in position by first laying two transverse rows of bricks in spaced relation to each other and then placing the packing sheet with the respective 60 brick rows extending into the channels 12 on the underside of the sheet. Another transverse row of bricks is then laid in the upper intermediate channel of the section of packing material between the spaced 65 brick rows which were first laid.

In Figures 5 to 8 of the drawings I illustrate another alternative method wherein a transverse row of bricks is first laid upon the car floor with one of their ends slightly spaced from the end wall of the car, as 70 shown in Fig. 5. The rolled sheet of corrugated paper 5' having a width approximately equal to the car width is then arranged in the car and the end 5'a of the corrugated sheet is positioned between the end of the bricks and the end wall of the car. The roll is then carried longitudinally and extended over the enameled upper faces 75 of the transverse row of bricks, as seen in Figure 6 of the drawings. In laying the next transverse row of bricks the corrugated paper is drawn downwardly between the opposed ends of the bricks in the adjacent rows. As seen in Figure 7 of the drawings, 80 the same relative arrangement of the corrugated paper and the bricks is attained as in the form of the packing sheet illustrated in Figures 3 and 4 of the drawings, which is cut into sections and provided with the brick receiving channels. After a complete 85 layer of bricks has been laid upon the car floor, the next superposed layer of brick is laid and the paper roll is manipulated so that the corrugated paper is positioned between the vertical and horizontally adjacent bricks, as seen in Figure 8 of the drawings. Of course it will be apparent that if desired, as the laying of each horizontal layer 90 of brick is completed, the corrugated paper sheet may be cut off from the roll. However, as suitable mechanical devices may be provided for handling or manipulating the roll of corrugated paper, I prefer to use a 95 rolled sheet of sufficient length that the packing sheet may extend continuously between the adjacent brick rows for the full capacity 100 of the car.

From the foregoing description considered in connection with the accompanying drawings, my improved method of packing enamel brick and the several advantages thereof will be fully understood. It will be apparent that by this method of packing, 105 using the corrugated sheet or strip material, the expense incident to properly protecting the brick against injury during transportation may be appreciably reduced in comparison to the expense incurred in the use 110 of the prior methods of packing, as pre- 115

viously referred to. Moreover, considerable time which has heretofore been consumed in placing the bricks in individual jackets or wrappers in the warehouse, is saved and as 5 the placing of the packing material takes place concurrently with the packing of the brick into the car, it is evident that the packing operation is very greatly expedited by means of my present invention.

10 I have herein referred to several embodiments of my improved method, but it is possible that other alternatives thereof might be devised and accordingly, it is to be understood that I reserve the privilege 15 of adopting such legitimate changes therein as may be fairly embodied within the spirit and scope of the invention as claimed.

I claim:

19 The method of packing brick in cars for 20 transport which consists in arranging the

brick in superimposed horizontal courses within the car with a plurality of transverse rows of bricks in each course, and interposing between said transverse rows of bricks as the courses are successively arranged in 25 position, a continuous sheet of cushioning material approximately of the same length and width as the interior of the car and having portions extending alternately above and beneath the transverse rows of bricks 30 and between the opposed ends of the bricks in adjacent rows to bond said transverse rows of bricks together and prevent relative shifting movement of the individual brick or contact of the horizontally or vertically 35 adjacent brick with each other.

In testimony that I claim the foregoing as my invention, I have signed my name hereunder.

J. FRANCIS BOORAEEM.
